(57) **CLAIM**

The ornamental design for a glare shield for an LED light fixture, as shown and described.

DESCRIPTION

FIG. 1 is a top perspective view of a glare shield for the LED light fixture, showing the new design;

FIG. 2 is a bottom perspective view of the glare shield for the LED light fixture;

FIG. 3 is a top plan view of the glare shield for the LED light fixture;

FIG. 4 is a left side elevation of the glare shield for the LED light fixture;

FIG. 5 is a bottom plan view of the glare shield for the LED light fixture; and,

FIG. 6 is an end elevation of the glare shield for the LED light fixture, an opposing end elevation thereof being identical.

The broken lines in the drawings illustrate portions of the glare shield for an LED light fixture that form no part of the claimed design.

1 Claim, 4 Drawing Sheets
